ABSTRACT: Plastic webs and films are heated to an elastomeric state, pressed while warm between a pair of crush rolls, and wound tightly around one of the crush rolls. Packages of the plastic webs and films prepared in this way are dense and free from air pockets.

PATENTED AUG 31 1971

3,602,449

Fig. 1.

INVENTOR.
EDWARD A. SROKA

WEB PACKAGING

This invention relates to the packaging of webs and films. More particularly it concerns novel arrangements for winding webs and films about cylindrical cores without entrapment of air bubbles.

In packaging many types of plastic sheet material, for example, films of polyvinyl chloride, the material is wound about cylindrical cores so that it can be easily stored and shipped. Materials of this nature, however, tend to experience surface irregularities in the nature of protrusions and indentations. As a result, when the material is wound about a core during packaging, these surface irregularities entrap air between the successive layers being wound. This situation results in a packaged product which is unduly bulky and which degrades the appearance of the film or sheet material. In addition wrinkles or creases may result as successive layers are tightly wound about each surface irregularity.

A film of polyvinyl chloride which is free from surface irregularities will on the other hand when tightly wound about a core provide a deep bluish appearance free from blemishes. The package will have a high density and will also provide a high quality appearance.

These desirable characteristics have been quite difficult to achieve. Attempts have been made to eliminate surface indentations and protrusions during winding by subjecting the film to tension while it is being wound. In most cases, however, this merely stretched the film thereby causing variations in thickness or caliper as well as in width. In the case of thin films especially any such decrease in thickness or caliper is unacceptable, for the film will tear or rupture. Attempts have also been made to eliminate surface irregularities by softening the material and reforming it through plastic deformation. These arrangements also have proved expensive, difficult to control, and generally unacceptable.

The present invention overcomes the above described difficulties of the prior art and permits tight winding of many plastic sheet materials about cores without air entrapment and without the air pockets, blemishes and other appearance-affecting characteristics which result from surface irregularities. Moreover the present invention accomplishes these results without the changes in thickness and width which result from known tension and stretching techniques.

The present invention is based in part on the recognition that forces may be applied to sheet material in a manner to flatten surface irregularities without affecting the overall character of the sheet so long as those forces are confined to the elastomeric deformation properties of the sheet material. According to the present invention, the sheet material is raised to a temperature at which it exhibits substantial elastomeric properties. Then, while the material is in this range, it is subjected to a high pressure ironing action produced by the nip of a pair of squeeze rolls. At the same time the material is wound tightly about one of the rolls. The squeeze rolls press down uniformly on the sheet. However in the region of each surface irregularity the material will be deformed elastically by the rolls to the same flattened configuration as the surrounding regions. Because the deformation is elastic rather than plastic the stresses built up at each irregularity are not dispersed by permanent deformations of the surrounding regions. The material is immediately wound tightly in this flattened condition and is thereafter maintained in its flattened condition by the winding. The resulting packaged product is thus free from surface defects and from entrapped air pockets.

According to another aspect the present invention involves the provision of a frame containing an internally heated drum, a back nip roll and a crush roll. The back nip and crush rolls press against the heated drum at displaced locations to enable sheet material to be held against the surface of the drum while passing over it. The frame is arranged to be actuated in a manner such that the crush roll is pressed tightly against a

takeup roll about which the sheet material is wound. The pressure between the crush and takeup rolls provides an ironing action for smoothing out surface irregularities in the sheet. Various further and more specific objects, features and advantages of the invention will appear from the description given below, taken in connection with the accompanying drawings, illustrating by way of example a preferred form of the invention.

In the drawings:

FIG. 1 is a perspective view, partially diagrammatic, illustrating a sheet packaging arrangement according to the present invention; and

FIG. 2 is an enlarged fragmentary cross section taken along line 2-2 of FIG. 1.

As shown in the drawings a web 10 of plastic sheet material, such as polyvinyl chloride, is supplied continuously from a sheet-forming station and a dancer roll tension device (not shown), and it passes through the nip of a back nip roll 12 and a heated drum 14. The web 10 continues around the outer surface of the drum 14 and between the nip of a crush roll 16 and the drum. Beyond this nip the web 10 remains in intimate contact with the outer surface of the crush roll 16 and passes through the nip of a takeup roll 18 and the crush roll 16. The web is wound up on the takeup roll 18.

As indicated schematically in FIG. 1, the back nip roll 12, the heated drum 14 and the crush roll 16 are mounted on a common frame 20 so that these rolls press tightly against each other. The frame 20 in turn is pivotally mounted, as indicated at 22 so that the crush roll 16 may move against and away from the takeup roll 18. This allows the system to accommodate the effectively increasing diameter of the takeup roll 18 as more and more of the web 10 is wound thereon.

Nip pressure between the crush roll 16 and the takeup roll 18 is obtained by means of a fluid actuator 24 which forces the pivotally mounted frame 20 in the direction of the takeup roll. Nip pressure can also be controlled by adjustment of the pressure in the actuator 24.

The heated drum 14, as shown in FIG. 2, comprises an outer surface portion 26 and an inner fluid-containing portion 28. Heating fluid 30 such as steam or hot water, fills the inner portion 28. As shown in FIG. 1 the heating fluid is circulated through the drum 14 by means of a piping system 32 and a pump 34. A heater 36 is also provided along the heating fluid circuit. The heater 36 is thermostatically controlled to maintain the temperature of the water passing through it. With this arrangement the drum 14 may be rotated continuously while a uniform temperature is maintained about its outer surface.

The crush roll 16 comprises a steel core 38 covered with a hard rubber (e.g. 70-80 durometer neoprene) cover 40, approximately 0.5-inch thick. The diameter of the crush roll 16 is considerably smaller than that of the drum. For example, the drum diameter may be approximately 12 inches while the crush roll diameter may be about 3½ inches.

In operation of the above described device, the web 10 passes over the back nip roll 12, around a sector of the heated drum 14 and over the crush roll 16. The back nip and crush rolls 12 and 16 hold the web 10 tightly against the surface of the drum over a sector of about 135°. The drum heats the web 10 uniformly during this time and brings it to a temperature where the web exhibits substantial elastomeric properties. The web 10 as thus heated is carried tightly around over the upper surface of the crush roll and is then pressed against the takeup roll 18 as it is being wound up thereon.

The heating of the web 10 by the drum 14 brings it to an elastomeric condition so that the pressure applied by the crush roll 16 will act upon any surface irregularities in the sheet and return them to a flattened condition without producing any plastic deformation which results in undesirable thickness or caliper changes. It will be appreciated that the longitudinal tension in the web 10 is kept below that in which caliper or thickness will change due to plastic deformation.

The heated drum 14 is of rather large diameter in order to provide sufficient drum surface area to bring the web 10 up to

temperature in a smooth uniform manner. This large diameter, however, does not permit the drum to exert high nip pressures. On the other hand, the small diameter crush roll 16, having a sharp curvature, concentrates its applied pressure against the takeup roll 18 more nearly in a line and the pressure in the nip of the crush and takeup rolls 16 and 18 can be made quite high. The small diameter of the crush roll 16 also serves to minimize the travel time of the web between the heated drum and the nip of the crush and takeup rolls. Consequently the web 10 remains in its elastomeric state during the ironing action of the crush roll 16 and winding action of the takeup roll 18. It will also be appreciated that with the heating drum 14, the crush roll 16 and the takeup roll 18 all in intimate contact at least one surface of the web 10 receives support during its entire travel through the packaging system. This serves to ensure that undue stretching will not occur.

The present invention provides excellent results when used to package polyvinyl chloride clear calendered sheeting of 0.005-0.020 gauge and medium hard. In one instance such sheeting was passed over the drum at a lineal speed of 20-50 yards per minute while the drum was maintained at a temperature of 85°-110° F. The pressure of the crush roll 16 against the takeup roll 18 was made sufficient to flatten all observable deformations in the sheet. The resulting packaged winding was characterized by an absence of imperfections caused by air pockets and it presented a high quality completely blue appearance.

It will be appreciated that the principles of the present invention are applicable to all sheet materials which are elastomeric or which exhibit substantial elastomeric properties within certain temperature ranges. However, especially good results are obtained with elastomeric vinyl halide polymer compositions. These compositions may be defined as containing vinyl halide homopolymers or copolymers plasticizers, stabilizers, and the other additives that are commonly used in this type of composition. The useful polymers

include, for example, polyvinyl chloride, polyvinylidene chloride, and vinyl chloride copolymers with vinyl acetate, vinyl butyrate, vinylidene chloride, styrene, methyl methacrylate, dialkyl fumarates, dialkyl maleates, etc.

5 What is claimed and desired to be secured by Letters Patent is:

10 1. Apparatus for packaging a web of sheet material, said apparatus comprising means for heating said web, ironing means for applying flattening pressure to both sides of the so-heated web, and means for winding the so-flattened, heated web into a dense package, said heating means and ironing means being mounted so as to press against each other and said winding means being pressed against said ironing means.

15 2. Apparatus according to claim 1 wherein said heating means comprises a heated drum, said ironing means comprises a crush roll, and said means for winding comprises a takeup roll.

20 3. Apparatus according to claim 2 wherein said heated drum and crush roll are mounted on a common frame so as to press against each other and said takeup roll is mounted so as to press against said crush roll.

25 4. Apparatus according to claim 3 wherein said frame is mounted for movement against said takeup roll and an actuator means causes said crush roll to press against said takeup roll.

5. The method for the packaging of a web of thermoplastic sheet material that comprises the steps of heating said web, ironing said web by applying a flattening pressure to both sides of the so-heated web, and winding the so-flattened web into a dense package, the pressure that is applied to both sides of the heated web being maintained during the heating and winding steps.

30 6. The method of claim 5 wherein the web is passed successively over a heated drum, a crush roll, and a takeup roll while 35 said rolls press against each other.
